FIG. 1 is a perspective view of an air freshener showing the new design.

FIG. 2 is an end elevational view of FIG. 1.

FIG. 3 is a side elevational view, taken from the right of FIG. 2.

FIG. 4 is a top plan view of FIG. 1;

FIG. 5 is an end elevational view, opposite the end elevational view of FIG. 2;

FIG. 6 is a side elevational view, taken from the right of FIG. 5; and,

FIG. 7 is a bottom plan view of FIG. 1.

(Continued)

The broken lines showing portions of the air freshener are included for the purpose of illustrating portions of the article and form no part of the claimed design.

1 Claim, 3 Drawing Sheets
